ELECTRICAL SOUND BLOOPING

Barton Kreuzer, Los Angeles, Calif., assignor to
 Radio Corporation of America, a corporation
 of Delaware

Application June 7, 1940, Serial No. 339,296

10 Claims. (Cl. 179—100.3)

This invention relates to sound motion picture apparatus and particularly to sound recording systems.

In the production of a sound motion picture it is well known that the finished picture is made up of a large number of separate sequences taken at different times during the production period of the picture. The concomitant sound sequences are generally taken simultaneously with the respective picture sequences. During the course of production, various numbers of sequences are spliced together for review, editing and rerecording purposes. In this procedure, the picture film and sound films are simultaneously projected and reproduced, respectively, and this is usually accomplished in individual picture and sound apparatus.

The first sound record, therefore, contains many splices which, when passing between the light source and photoelectric cell in the sound head, produce "plops" or "clicks." To prevent these extraneous noises, several methods have been employed in the past, such as the manual painting out of the splices by black paint applied to the splice point or over the images of the splices, or by a mechanical shutter arrangement in the sound head itself. This procedure of eliminating the effect of a splice is known as "blooping," one form of the shutter type of bloopoer being illustrated in U. S. Patent 1,810,527, of January 16, 1931.

The present invention is directed to a specific form of blooping system wherein the effect of a splice or any other extraneous density variations in the sound track portion of the film is prevented from interfering with the sound track reproduction. In the usual type of shutter bloopoer the light beam of constant intensity is gradually eliminated from the sound track at the splice, and consequently from the photoelectric cell, and then gradually returned to the film, the desired periodicity of the increase and decrease in light being below audibility. In other words, the elements varying the light beam must be so timed as not to introduce noise by their own operation.

The present invention is directed to a method of and system for varying the transmission in the reproducing circuit intermediate the sound head and a sound rerecorder loudspeaker or monitor, the rate at which the transmission is decreased and increased being determined by electrical timing circuits. In this manner the timing is easily controllable with accuracy, the entire system lending itself to a better overall

operating characteristic than is found in the use of mechanical devices which must be built into the sound head itself.

With the present invention the only element located at the sound head is a circuit contactor operable by either holes in the film, notches in the film, metallic elements adhering to the film, or by the increase in thickness of the film caused by the film splices themselves. When an electrical contact is produced by one of these modifications to the film passing a predetermined point, a relay may be actuated which will modify the transmission characteristic of the reproducing transmission circuit to reduce transmission or increase attenuation at a certain predetermined rate and to restore the circuit at another rate, these rates being such as not to introduce an audible variation at the loudspeaker or upon the film when the rerecorded sound track is reproduced.

The principal object of the invention, therefore, is to facilitate the reproduction of spliced sound record film or film having variations in light densities thereon which cause extraneous reproduced noises.

Another object of the invention is to electrically reduce and restore the transmission of a reproducing sound circuit at an inaudible rate.

A further object of the invention is to bloop a sound record film by varying its transmission circuit.

A further object of the invention is to provide a timing circuit for an electrical transmission circuit which introduces an inaudible variation in the reproduced sound.

A further object of the invention is to control the shunt impedance of a transmission circuit at a predetermined rate under control of a reproduced film being transmitted by the circuit.

Although the novel features which are believed to be characteristic of this invention are pointed out with particularity in the appended claims, the manner of its organization and the mode of its operation will be better understood by referring to the following description read in conjunction with the accompanying drawings forming a part thereof in which

Fig. 1 is a combination schematic and diagrammatic drawing embodying one modification of the invention;

Fig. 2 is a detail of a variation of the modification shown in Fig. 1;

Fig. 3 is a schematic drawing of another modification of the invention; and

Figs. 4 and 5 are detail views showing variations of the modification shown in Fig. 3.

Referring now to Fig. 1, a sound head 5 having a film magazine 6 translates the variations in transmission through the sound track area of a film into electrical currents which are transmitted over conductors 7 to a transformer 8. Transformer 8 feeds an amplifier tube 9 which is coupled by resistances 10 and 11 and a condenser 13 to a standard amplifier 15, the amplifier 15 feeding a sound recorder 16 with its film magazine 17 when switch 20 is closed. For monitoring and rehearsal purposes a loudspeaker 18 is provided.

In the sound head 5 is shown diagrammatically a contact switch 22 which may be of any standard type operable by film notches or any other modifications to the film being reproduced as mentioned above. The contacts 22 are connected over conductors 23 through a potential source 24 to a relay 25. Energization of the relay 25 will close a contact 26, thus closing a circuit through a potential source, such as a battery 27, a resistance 28, a potentiometer resistance 29 shunted by a potential source, such as a battery 30, and the cathode and grid of tube 33, these elements just recited being connected in series. Shunted across the contact 26, battery 27 and resistance 28 is a condenser 34 and a resistance 35.

The tube 33 has its anode to cathode impedance shunted across the transmission circuit connecting tube 9 with amplifier 15. By the initial adjustment of the potentiometer resistance 29, the impedance of tube 33 is made high so that this tube normally has a negligible effect upon the transmission circuit. It will be observed that the cathode is connected to ground at 37, while the positive terminal of potentiometer resistance 29 is also connected to ground. Thus the transmission of the electrical currents from the sound head 5 over the transmission circuit will be normal with the contact 26 open. When the contact 26 is closed, however, by the energization of relay 25, the grid of tube 33 is given a positive potential from the battery 27 which will reduce the anode-cathode impedance of the tube and thus lower or attenuate transmission over the reproducing circuit. The amount of this reduction is, of course, controlled by the value of the potential source 27, resistance 28, the setting of potentiometer resistance 29, and the ratio of resistance 35 to resistances 35 and 28.

The rate of attenuation is primarily determined by the values of the resistance 28 and resistance 35, while the rate at which the system will be restored to its normal operating characteristic after the contact 26 is opened is primarily determined by the rate of discharge of condenser 34 through resistance 35. This timing circuit just described is easily adjusted and predetermined so that the decrease in the transmission characteristic and increase therein may be at a rate sufficiently low as not to be audible at the speaker 18. Furthermore, there will be no transmission to the sound track modulating elements in the recorder 16 while contact 26 is closed.

Referring now to Fig. 2, it will be observed that a shunt tube 39 is positioned in the reproducing circuit similarly to the tube 33 of Fig. 1. However, in this circuit the tube 39 is self-biased through a resistance 41, the timing being obtained through the impedance characteristics of the associated circuit elements. That is, when

the contact 26 is open, which is the normal position, the tube 39 will have a high impedance due to a negative grid caused by current flow through the resistance 41. However, when the contact 26 is closed, the grid is brought to the same potential as the cathode, and the impedance is materially decreased. This circuit, of course, will provide a more rapid action than the timing circuit of Fig. 1.

10 Referring now to Fig. 3, a standard type of rerecording amplifier circuit is disclosed in which the input to a transformer 43 is connected to the sound head, while the output of the transformer is impressed upon a screen grid tube 44. The 15 output of tube 44 is coupled to an amplifier tube 45 by resistances 46 and 47, a condenser 48 and a timing circuit composed of a resistance 49 and a condenser 50. The output of tube 45 is transmitted through a transformer 52 to another amplifier, such as is shown at 15 in Fig. 1. The potential supply for the screen grid tube 44 is obtained from a B-supply connected at 54 to a potentiometer comprising resistances 55, 56 and 59 and a series resistance 57. The anode potential for tube 44 is obtained over resistance 57, a contact 58 and resistance 46, while the screen grid potential of tube 44 is obtained over resistance 57, contact 58 and a resistance 60. The B-minus potential is connected to the potentiometer at 62; one lead to the photoelectric cell is connected at 63; the cathode is connected at 61, while conductors 64 from relay 65 go to a film-controlled contacting device such as shown at 22 in Fig. 1.

In the operation of the above circuit, the transmission tube 44 itself is operated upon to reduce or attenuate transmission therethrough at a predetermined rate. The normal condition of contact 58 is closed, as shown, so that the anode and screen grid of tube 44 is energized from the B-supply. However, upon actuation of the relay 65 which opens contact 58, the anode and screen grid potential is removed from the tube 44 at a rate principally determined by the discharge of condenser 66 shunted across the anode-cathode and screen grid-cathode circuit. By-pass condenser 67 and certain other circuit elements also have a slight effect on the rate of attenuation. The restoration rate for the tube 44 when the contact 58 is closed is determined by the value of the resistances 57, 46 and 60 and condensers 66 and 67. Thus, by varying the values of resistances 57, 46 and 60 and the value of condenser 66, a definite rate of decrease and increase in the transmission rates is obtainable which will provide an inaudible signal either at the monitor speaker 18 or at the recorder.

60 A variation of the timing circuit shown in Fig. 3 is shown in Fig. 4, wherein the anode and screen grid of tube 44 is connected at point 68 on the potentiometer 55, 56 and 59, the cathode, to the point 69, while the positive B potential terminal is connected through resistance 51 and a contact 71. A condenser 72 is bridged across potentiometer resistances 55, 56 and 59. In this variation, breaking of the contact at 71 removes the B potential from the anode and screen grid of tube 44, and the rate of decrease in transmission of the tube is dependent upon the rate of discharge of condenser 72 through resistances 55, 56 and 59 and other circuit elements. The restoration period, of course, is determined primarily by the value of resistance 51 and resistances 46 and 60, as in Fig. 3.

In Fig. 5, only the potential on the screen grid

of tube 44 is varied by the relay 65. In this embodiment, the potential to the screen grid is supplied over a resistance 74 through contact 75 to the B potential supply shunted by a condenser 76. The contact 75 is normally closed while the contact 77 is normally open. Upon actuation of the relay 65, however, contact 75 is broken and contact 77 is made, which removes the B supply from the screen grid and lets it decay at a rate determined by the rate of discharge of condenser 76 through resistance 74. Upon de-energization of relay 65, however, restoration of transmission to the circuit is controlled by the value of resistance 74. The values of other circuit elements, of course, modify the values of the resistance 74 and condenser 76.

In the above modifications, electrical control of transmission attenuation is produced by a variable shunt in the transmission circuit and by varying the attenuation of one of the transmission elements itself. In each case, the variations in the rate of transmission decay and restoration is easily controllable so that any desired characteristic may be obtained. Furthermore, this type of control may be introduced in the circuit away from the sound head except for the small contacting device which may be positioned at any easily accessible point either in the sound head or in the film magazine, which arrangement does not interfere with the optical elements in the sound head itself. In a mechanical shutter system, if the edge of the shutter does not intercept the light beam properly to produce inaudibility of the blooping operation, it is difficult to alter the condition. With the present electrical blooping circuit any resistance or condenser may be made variable for this purpose. Furthermore, the circuit may be manually controlled if such operation is desired.

I claim as my invention:

1. A sound transmission system for a sound record having extraneous modulations therein comprising means for translating said record into electrical currents corresponding thereto, means for transmitting said currents, means for attenuating the transmission of said currents at intervals corresponding to the periods of translation of said extraneous modulations, and means for producing a predetermined rate of attenuation and restoration.

2. In a sound system, the combination of a sound record film having extraneous light density variations thereon, means for translating said record into electrical currents, a circuit for transmitting said currents, means in said circuit for varying the attenuation of said currents at the intervals of translation of said extraneous light density variations, and means for controlling the rate of attenuation of said circuit during said intervals, said attenuation varying means including a vacuum tube and said controlling means including a source of potential for and connected to the elements of said tube and a condenser and resistance connected intermediate said tube elements and said source of potential.

3. In a sound system, the combination of a sound reproducer, a sound record adapted to be

advanced through said sound reproducer, said sound record having splices therein, a loudspeaker, an electrical circuit interconnecting said sound reproducer and loudspeaker, and a variable shunt impedance comprising a vacuum tube connected in said circuit, variations in the impedance of said vacuum tube being under control of said sound record in said reproducer, and means interconnecting said tube and said reproducer for controlling the time intervals of said impedance variations in said tube and the rate of said impedance variations.

4. A sound system in accordance with claim 3 in which said time interval control means includes an electrical contactor in said sound reproducer, and said rate control means includes an electrical timing circuit in the input circuit of said vacuum tube.

5. In a sound system, the combination of a sound record film, circuit means for reproducing the sound record on said film, one of said circuit elements comprising a vacuum tube having grid, anode and cathode, means for supplying potential to the anode of said tube, means under control of said sound record for eliminating said potential on said anode, and means connected intermediate the potential supply for said anode and said anode for predetermined the rate of decay of said anode potential and the rate of restoration thereof.

6. A sound system in accordance with claim 5 in which said last-mentioned means comprises a film-controlled switch for eliminating the anode potential and a condenser-resistance timing circuit connected intermediate said anode and cathode and said anode potential for determining the rate of decay of said anode potential and the rate of restoration thereof.

7. A sound blooping system comprising a sound record having extraneous densities therein, means for translating said record into electrical currents corresponding thereto, means for transmitting said currents, means for attenuating the transmission of said currents at intervals corresponding to the periods of translation of said extraneous densities, and means for producing a predetermined rate of attenuation and restoration.

8. A sound blooping system in accordance with claim 7 in which said attenuating means comprises an electronic shunt across said current transmission means and an electrical timing circuit for predetermined the variations in impedance of said electronic shunt.

9. A circuit for controlling the transmission thereover comprising an amplifier, a potential source connected to said amplifier, a switch connected in the potential supply to said amplifier, and a condenser-resistance network connected intermediate said potential source and said amplifier for removing and connecting said potential source to said amplifier at an inaudible rate.

10. A circuit in accordance with claim 9 in which said switch is signal-controlled to prevent extraneous signals from being transmitted over said circuit.

BARTON KREUZER.
